UNITED STATES PATENT OFFICE.

JAMES A. TAYLOR, OF NEW YORK, N. Y.

ENGINE STARTING MECHANISM.

1,297,750.

Specification of Letters Patent. Patented Mar. 18, 1919.

Original application filed July 14, 1911, Serial No. 638,572. Divided and this application filed December 16, 1914. Serial No. 877,536.

To all whom it may concern:

Be it known that I, JAMES A. TAYLOR, a citizen of the United States, residing at the borough of Manhattan, in the county, 5 city, and State of New York, have invented certain new and useful Improvements in Engine Starting Mechanisms, of which the following is a specification.

The objects of my invention are to provide an engine or motor starting device, actuated by power, (usually compressed-air) for giving the initial starting movement to the explosive vapor or other motor used; and is shown herein as applied to road vehicles of the automobile type; although not limited to use therein. As shown herein in the particular form I prefer to use in adapting my said invention to use in road vehicles, the same is combined usually with the 10 ordinary combined fly-wheel and clutch mechanism; with a power braking mechanism; and also usually with a power gear-shifting mechanism, preferably of the improved form of my invention, fully set forth 15 described and claimed in my original application Serial No. 638,572, of which this is a division; wherefore I have not deemed it essential to show or describe herein the controlling-keys, or connecting mechanism.

To the before mentioned ends my said invention comprises in the main, a main or motor crank-shaft; a drive-shaft; two drive-clutch members adapted to bring such two shafts into and out of operative connection with one another; a motor-starting mechanism carried by the main or crank-shaft comprising a clutch-member reciprocating on and rotating with the crank-shaft, coacting with a clutch-member revolvably 20 mounted on the crank-shaft; means for reciprocating the reciprocating clutch-member; means for forming a yielding contact between such clutch-members; mechanism connecting the drive-clutch with the starter-clutch mechanism, in such manner that when one is in the clutching position; the other will be out; means actuated by the driver for throwing the drive-clutch out without throwing the driver-clutch in, a braking 25 mechanism; power mechanism controlled by the driver which when moved in one direction will set the braking mechanism, and

when moved in the other will actuate the starting mechanism so as to give the initial starting rotative movement to the crank-shaft of the motor; means for automatically returning the rotating member of the starter-clutch to the normal position upon release from the power; means for automatically returning the braking-mechanism to the non-braking position upon release from the power; means for locking the drive-clutch against being thrown into clutch while the starting mechanism is being operated; means for automatically throwing the drive-clutch 30 out upon the neutralization of the shift-gears, and for releasing such drive-clutch upon the throwing into clutch of a shift-gear; and mechanisms connecting and combining all such described mechanisms into 35 a concrete whole in such manner, that no one can be operated in a way to bring injury to any; although I do not limit myself to the exact construction, nor combination shown, either in whole, or in any of the parts 40 thereof.

My said invention is fully shown and described in the following specification, of which the accompanying drawing forms a part, wherein similar letters or numerals of 45 reference designate like or equivalent parts wherever found throughout the several views; and in which:

Figure 1 is a side-view, partially in section, of the combined drive-clutch and motor starting mechanism, with its connection with the neutralizer interlocking mechanism;

Fig. 2 is a top-plan view of the neutralizer mechanism and its supporting frame;

Fig. 3 is a top view of the right hand portion of the mechanism shown in Fig. 1, showing the starter-mechanism, and its connection with the brake-rod, etc.

Fig. 4 is a diagrammatic view of the 50 starter-cable and spring retracting-mechanism, taken in section on the line $h-h$ of Fig. 1, looking toward the right;

Fig. 5 is a diagrammatic side-view of the 55 double power braking mechanism, showing the connection thereof with the starter-mechanism;

Fig. 6 is a top-plan view of the motor-starter and drive-clutch locking mechanism,

shown in side-view as a portion of Fig. 1; and

Fig. 7 is a top-plan view of the right side portion of the forward braking mechanism, etc.

Referring to the drawing;—

As shown in Figs. 1, 3, 4, 5, 6 and 7, in the form of embodiment of my invention I prefer to use, my improved motor-starter, etc., 10 usually combined with a combined fly-wheel and drive-clutch mechanism of any of the forms in common use; which usually comprises a fly-wheel A, rigidly secured to the end of the motor main or crank-shaft B, 15 (usually by a suitable key 1) so as to rotate in unison with such shaft B; with which fly-wheel coacts the other and movable member E, of such drive-clutch, for forming the required connection between the crank-shaft 20 B, and the drive-shaft D, in actuating connection at its rear end with the main driving gear-wheel (not shown), adapted to actuate the usual speed shift-gears (not shown), commonly used in motor vehicles, when in 25 mesh therewith.

While any form of clutch may be used as a drive-clutch, the common reciprocating-cone construction clutch shown is especially well adapted for use with my improved motor 30 starter-mechanism; and as shown comprises the clutch-cone E, formed integral with the rear sleeve portion E', keyed to the drive-shaft D, so as to rotate therewith while reciprocating freely longitudinally thereon, in 35 the manner common in such clutch devices.

The fly-wheel is provided on its front face with a cylindrical chamber surrounding the crank-shaft B, which is closed by a two part split-plate 2, having a central orifice so as 40 to prevent the starter-sleeve F, from slipping outward by reason of having its inner edges located in the peripheral retaining-groove thereof, as clearly shown in Fig. 1; the split-plate 2 being usually secured in 45 place by suitable screws 2'.

The starter-sleeve is vibrated by the starter-cable 4, fitting in a groove on the larger periphery of such sleeve F, and secured at the end thereon; and is provided 50 on its outer face with a crown-toothed ratchet-wheel 6. Also secured in like manner to the sleeve F, (usually between the cable-wheel portion and the fly-wheel, as shown) is the retracting coil-spring 7, for 55 automatically returning such sleeve to its normal position upon release of the starter-cable 4, from the starter power mechanism.

Reciprocatingly mounted on the crank-shaft B, and usually secured in place by 60 means of a set-screw 8, passing through the same into a longitudinal slot in the shaft B, so as to slide freely thereon while rotating therewith, is the reciprocating starter-clutch member or sleeve G, having on its rear face a 65 crown toothed ratchet-wheel 9, co-acting

with the like ratchet-wheel 6, to form a clutch.

Secured in place upon the shaft B, (usually by a set-screw 10) is a stop-collar 11, between which and the reciprocating starter-clutch member G (and mounted on the shaft B) is located the coil starter-clutch pressure-spring 12, for normally forcing the member G, into clutch with its co-acting member F, unless restrained.

The letter H, designates a bracket rigidly secured to the main frame of the vehicle having journal-studs 13, in which is reciprocatingly mounted the slide-bar 14, having at one end the fork 15, and at the other the like fork 16, each of the well-known form, having studs 17, projecting into peripheral grooves 18 and 19 in the drive-clutch member C, and reciprocating starter-clutch member G, so that reciprocation of the slide-bar 14, will bring such drive and motor-starting clutches into and out of clutch alternately. That is, the construction is such, that the drive-clutch cannot possibly be brought into clutch without throwing the starter-clutch 90 out and vice versa. In order that the starter-clutch members may be disengaged when the motor begins to rotate, the peripheral slot 19, of the starter reciprocating clutch-member G, is much wider than the fork-pins, 95 whereby upon the rotation of the crank-shaft B, the reciprocating member G, will be forced back against the resiliency of the coil-spring 12, so as to slip by the vibrating clutch-member or starter-sleeve F.

As shown in Figs. 3 and 4, the starter-cable 4, is secured at its outer end to a rod or stud 20, formed integral with a slide-block or gib 21, reciprocating in the slide-way of the slide-way frame 22, rigidly secured 100 to the main-frame of the chassis of the vehicle (not shown). Such slide-block or gib 21, is rigidly secured to the piston-rod 23, carrying a piston (not shown) reciprocating in the fluid-pressure cylinder J, whereby, 105 by manipulation of the proper keys (not shown), controlling the entrance and exhaust of the compressed-air, or other actuating pressure fluid, at either end of such cylinder, such piston-rod 23, will be forced to the front (toward the right of Figs. 3 and 4,) to actuate the starter-mechanism, and to the rear (or left) to actuate the brakes; the piston being kept normally in the central 110 or neutral position, when not under pressure 115 by the resiliency of the spring steel strap-brakes 24 and 25.

The starter-cable 4, passes to the starter-clutch vibrating member 6, by way of the idler-pulley 26, secured upon a side extension or bracket 27, of the slide-way frame 22; and secured upon such starter-cable is a stop-collar 28, abutting against the forward face of the bracket 27, to prevent destructive 120 excessive retractive movement of the member 130

6, when returned to its normal position by the action of the coil-spring 7; and formed integral with or firmly secured to the slide-block 21, is a shift-rod 20 abutting against 5 the stem-rod 15', of the starter-clutch fork 15, so as to just throw out the drive-clutch member C, when the piston-rod 23, is moved to the rear (or left of drawing) in order to set the brakes, without bringing into clutch 10 the reciprocating clutch-member G, of the starter mechanism.

Pivoted to the bracket H, by means of a pivot-hole 30, is a shift-fork 31 having shift-pins 32, projecting into the peripheral shift-slot 33, of E', so as to release the drive-clutch, when the top fork portion of the shift-fork 31, is moved to the rear or left 15 of Fig. 1. And in order that the driver of the vehicle may do this by foot-pressure upon the usual clutch-release pivoted pedal-lever 34, such lever is so shaped at the lower portion 34' as to do this by abutment against the throw-stud or lug 35, of 31, but this throw-out movement while sufficient to release 20 the drive-clutch, is not sufficient to throw in the starter clutch reciprocating member G, so as to throw the same into position to be actuated by the piston of the rod 23; this limitation of movement being 25 brought about by abutment of the lever 31, against the stop-stud 36.

Abutting against the lower end of the vibrating shift-fork lever 31, is the rod 37, having the adjustable stop-nuts 38, screwed 35 thereon, by which when thrown forward by abutment of such nuts against the lower end of the lever-fork 31, when the rod 37 is thrown to the front, or right of Fig. 1, the clutch will be thrown out the same distance 40 only, as is the case when thrown out by the foot-lever 34. And such clutch throwout rod 37, is so thrown forward upon the neutralizing movement of the neutralizer gear-shift mechanism, shown in detail in Fig. 2, 45 and is automatically locked in such position, (so as to keep the clutch thrown out) until the locking mechanism is automatically released upon the throwing into mesh of a shift-gear, when the throw-spring of the 50 drive-clutch (not shown) will instantly throw it to its normal clutching position.

As shown in Fig. 2, the frame supporting the neutralizing and gear-shifting mechanism, is usually of rectangular form, and is 55 secured to the chassis or main frame of the vehicle in front of the shift-gear box (not shown). And reciprocatingly secured in side-slots 39, of the side-pieces 40 of such frame, are the end slide-studs 41, of the top 60 neutralizing slide-bars 42 and 42', having secured beneath the same and reciprocating on bolts 43, bottom-bars, (not shown), normally pressed upward against the top-bars by suitable springs (not shown). The slide-bars are kept normally pressed apart to the 65 limit of the slide-slots 39, by suitable springs 44; and located between them and reciprocatingly journaled in the side-pieces of the frame, are the two shift-gear rods 45 and 46, provided on the under face with slip locking 70 cam-slots (not shown) for locking the slide-bars 42 and 42', in the central and neutralizing position, into which they are drawn by the forward movement, (toward the right of Fig. 2) by such movement of the combined 75 neutralizing and reversing-gear rod 47; which is provided with a collar 48, located outside of the slide-bar 42, to move the same, the coacting bar 42', being simultaneously moved toward the center in the opposite direction, by the action of the levers 49, 50 and 51, pivoted as shown.

In their neutralizing position the bars are locked in place by the locks of the bars below 42 and 42', while the neutralizing rod 80 is only locked when thrown to the extreme left so as to throw in the reversing-gear.

Reciprocating in the side-pieces 40, outside of the slide-bars 42 and 42', are the slide-rods 52 and 52', having the upwardly 90 extending cam-studs 53, by contact with which the central side-cams 54, of the gear-shift and the neutralizer and reverse-gear rods 45, 46, and 47, will be moved to what is the top of Fig. 3, when the rods 45, 46 and 95 47, are reciprocated in the proper direction. Each of these slide-rods 52 and 52', is connected pivotally through a suitable stud (not shown), with a rock-rod 55, vibratory journaled at the ends in the front and 100 rear side-pieces of the frame 38, in such manner that when actuated by the cams 54, they will either of them vibrate such rod 55, toward what is the bottom of Fig. 3; and such rod 55, is provided with a coil tension 105 spring 56, secured thereto and to the frame 38, whereby upon release from the pressure of such cams the rod 55, and also the rods 52 and 52', will be returned to the normal position.

The rock-rod 55, is provided with a toothed-rack 57 faced toward the front (right of Fig. 3), adapted to receive a spring-dog pawl 58, carried by the reciprocating clutch-throwout-rod 37, which is released therefrom upon the throwing into mesh of either of the four speed-gears, by the reciprocation in either direction of the shift-gear rods 45 and 46, (or by the reciprocation to the rear of the combined reverse-gear and neutralizer rod 47) by the consequent vibration of the rock-rod 55, carrying the rack 57. For this purpose a stud-arm 60, rigidly secured to the neutralizer-rod 47, upon its movement in the forward and neutralizing direction (to the right of Fig. 3) abuts against a collar or stop 61, rigidly secured to 47, so as to force 37 to the front; and the stop-nuts 38 thereon, acting on the lower end of the pivoted shift-fork 31, forces 130

the same to the front so as to release the drive-clutch member C, whereupon the pawl 58 locks the clutch in the released position, until the throwing in of any of the five gears 5 (four speed and one reverse), releases such pawl, when the spring of the clutch will return such rod to its normal unlocked position.

Inasmuch as such gear-shifting and neutralizing mechanism, except in combination, forms no part of the invention herein claimed; and may therein be of forms different from the construction set forth; and that the same is fully described; set forth 15 and claimed in my before mentioned original application of which this is a divisional application, I have not deemed it essential to more fully show or describe the same herein; as many mechanisms performing the 20 same functions, may be used in the combination herein claimed, without departing from the scope of my invention.

If the starter-mechanism should be actuated when the starter-clutch is out of mesh, 25 such action would be liable to wreck such mechanism; and to obviate this I prefer to provide a suitable locking mechanism; such for instance as that shown at K, (Figs. 1 and 6) which prevents the pressure fluid 30 from being allowed to enter the cylinder J, on the starter actuating side (left of drawing), save when such starter-clutch is in mesh. Such locking mechanism may be of many forms, but that shown will be found 35 efficient.

In same (as shown in Figs. 1 and 5,) a bracket-piece or plate 66, is formed integral with or secured to the standard 16', of the shift-fork 16, and is provided with a narrow slip-slot 67, having at its forward end (right of drawing) the enlarged lock-slot or orifice 67', usually of the circular form shown, but at any rate of the same shape and diameter in cross-section as is the enlarged lower lock-portion 68, which together 40 with the upper projecting slide-pin 68', formed integral therewith, constitutes a reciprocating lock-pin L; which when in the normal lower position shown will only have 45 the slide-pin 68', in the slot slide-way formed by the slot 67—67', so as to allow of free reciprocation of the bracket K, and its attached bar 14; but the lock-bolt L, composed of 67 and 67', is so connected with 50 the hand-lever or key admitting the pressure-fluid to the starter side of the cylinder J, (left of drawing, neither key nor valve shown), in such manner that upon the actuation of such key by the driver, it will in 55 its initial movement, and before the opening of the valve so as to admit the pressure-fluid to the cylinder, throw such lock-pin L, up into the circular enlarged portion 67', of the lock-slot, thus locking the starter- 60 clutch in, save for the yield of the spring 65

12; after which continued movement of the key in the same direction will open the valve as the lock-pin moves farther upward, when the starter-clutch will be rotated; and it will be seen that except when the clutch of the 70 starter-mechanism is fully in and the drive-clutch is out, can the lock-pin L, be forced sufficiently far upward to admit pressure-fluid to the cylinder J, so as to rotate the 75 starter-mechanism.

Inasmuch as the particular mechanisms herein stated to be "not shown" are more fully and specifically set forth, described and claimed in the original application of which this application is a divisional one, 80 such original being my application Serial No. 638,572, filed July 14, 1911, or in another divisional application of such original, Serial No. 877,538, filed December 16, 1914, simultaneously herewith, I have not deemed 85 it essential to more fully show or describe the same herein.

I claim:—

1. In a device of the class described, a main or motor crank-shaft; a combined fly-wheel and clutch-member rigidly secured to the main or crank-shaft; a transmission shaft; a clutch-member secured to the transmission-shaft coacting with the fly-wheel clutch member; a motor-starter clutch-member provided with outwardly faced ratchet-teeth concentric to the main or crank-shaft revolvably mounted thereon, and so secured in the abutting face of the fly-wheel; a motor-starter clutch member, having crown-ratchet teeth coacting with the like teeth of the other motor-starter clutch-member when in mesh therewith, mounted upon the main or crank-shaft so as to be longitudinally movable thereon while revolvably therewith; mechanism controlled by the driver for moving such longitudinally movable motor-starter clutch-member longitudinally of the main or crank-shaft so as to bring the same into and out of clutch with the first 110 motor-starter clutch-member, and power actuated means for causing actuation of the fly-wheel motor-starter clutch-member vibratory upon the main or crank-shaft when in clutch with the longitudinally movable 115 motor-starter clutch member, in such manner as to give an initial motor-starting movement to the main or crank-shaft.

2. In a device of the class described, a motor-starting device comprising a clutching-mechanism having a clutch-member carried by the main or crank-shaft rotating therewith and reciprocating thereon; a second clutch-member supported by the main or crank-shaft adjacent to the reciprocating-member in which such shaft is free to rotate; mechanism controlled by the driver for reciprocating the reciprocating member into and out of clutch; and power means for causing actuation of the second clutch-member vi- 130

bratorily upon the main or crank-shaft, in such manner as to give an initial motor starting movement to the main or crank-shaft.

5 3. In a device of the class described, a motor-starting device comprising a clutching mechanism having a clutch-member carried by the main or crank-shaft rotating therewith and reciprocating thereon; a second clutch-member supported by the main or crank-shaft adjacent to the reciprocating-member in which such shaft is free to rotate; mechanism controlled by the driver for reciprocating the reciprocating member 10 into and out of clutch; means for causing actuation of the second clutch-member vibrately upon the main or crank-shaft, in such manner as to give an initial motor starting movement to the main or crank-shaft; and means for automatically returning such second clutch-member to its initial normal position upon its disengagement from the reciprocating clutch-member.

4. In a device of the class described, a motor having a main or crank-shaft; a clutch-member secured upon such shaft so as to reciprocate thereon and rotate therewith; a coacting-clutch member vibrately mounted upon such main or crank-shaft, in 15 which such shaft is free to rotate; crown wheels or clutch engagements carried by each of such clutch-members; and power means controlled by the driver for moving the vibrating clutch-member in such manner as to give an initial actuating rotative motor-starting movement to the motor or crank-shaft.

5. In a device of the class described, a motor having a main or crank-shaft; a clutch-member carried by such crank-shaft rotating therewith and reciprocating thereon; a second coacting clutch-member supported upon such shaft vibrately mounted thereon, in which such shaft is free to rotate; means controlled by the driver for bringing such clutch-members into and out of operative engagement; means for vibrating the non-reciprocating clutch-member when in clutch with the coacting clutch-member in such manner as to give an initial 20 motor starting rotative movement to the main or crank-shaft of the motor; and a spring for returning the vibrating motor-starting-clutch member to its initial normal position.

6. In a device of the class described, a motor having a main or crank-shaft; a clutch-member rigidly secured upon the main or crank-shaft; a drive-shaft; a second clutch-member co-acting with the first clutch member rotating with and reciprocating on the drive-shaft; a crown-ratchet-wheel carried by the main or crank-shaft and reciprocatingly mounted thereon rotating there- 25 with; a reversely faced coacting like crown-

ratchet-wheel mounted on such main or crank-shaft in such manner that such shaft may rotate freely therein; mechanism connecting the moving member of the drive-clutch with the reciprocating crown ratchet-wheel in such manner that when the drive clutch is in working position, the crown ratchet wheels will be out of contact, and vice versa; power actuated mechanism for vibrating the non-reciprocating ratchet-wheel so as to give an initial motor starting rotative movement to the main or crank-shaft; and means for actuating the drive-clutch.

7. In a device of the class described, a 30 rotating non-reciprocating clutch-member; a coacting moving clutch-member adapted to be brought into and out of clutch with the rotating clutch-member; a motor; means or mechanism for giving the initial starting 35 movement to the motor; and means or mechanism for automatically disengaging the starting mechanism from the motor-shaft, upon throwing the first clutch into mesh.

8. In a device of the class described, a motor, having a main or crank-shaft; a pressure-fluid reservoir; a crown-ratchet-wheel rotating with the main or crank-shaft and reciprocating thereon; a reversely faced co- 40 acting like crown ratchet-wheel mounted freely rotatively thereon; means actuated by the pressure fluid for rotating the freely rotating wheel in the motor starting direction; means for automatically returning the 45 rotative-wheel to its initial normal position; and means controlled by the driver for actuating the inlet and exhaust valves of the 50 starter-actuating power-mechanism.

9. In a device of the class described, a 55 starter-mechanism comprising a member adapted to give an initial starting rotative movement to the main or crank-shaft of the motor, in which the main-shaft is free to rotate thereafter; means for automatically 60 returning such member to the initial motor starting position, upon release from the starting force; and means controlled by the driver for putting such mechanism into 65 operation.

10. In a device of the class described, a 70 motor starting mechanism comprising two clutch-members adapted to be brought into and out of clutch so as to initially start the motor, and release the motor from the 75 initial starting mechanism automatically upon its operation; power means for operating the motor-starter; a drive-clutch for bringing the motor into and out of connection with the driving mechanism of the vehicle; means for preventing mechanical interference of the drive-clutch and motor-starter, in such manner that the motor-starter cannot be operated when the drive-clutch is in; and mechanism controlled by 80

the driver controlling or actuating all such mechanisms.

11. In a device of the class described, a motor-starting mechanism; a motor-vehicle braking mechanism; and power means for actuating both such mechanisms in such manner that they will each be actuated by reverse actuation of the same actuating mechanism.
- 10 12. In a device of the class described, a motor-starting mechanism; a pressure actuated piston; a braking device; mechanism

connecting the motor-starting device with the braking device in such manner that while they are actuated from a common source of power, their reverse action will in no manner interfere with the other. 15

Signed at the borough of Manhattan, city, county, and State of New York, this 12th day of December, 1914.

JAMES A. TAYLOR.
